United States Patent Office

Des. 233,912

Patented Dec. 10, 1974

233,912

ELECTRONIC FLASH UNIT

Albert L. Nagele, Wilmette, Ill., assignor to
Bell & Howell Company, Chicago, Ill.

Filed June 25, 1973, Ser. No. 373,346

Term of patent 14 years

Int. Cl. D16—05

U.S. Cl. D61—1 F

Fig. 1.

Fig. 2.

FIG. 1 is a front, top, and side perspective view of an electronic flash unit showing my new design; and

FIG. 2 is a rear, bottom and opposite side perspective view thereof.

I claim:

The ornamental design for an electronic flash unit, as shown and described.
